UNITED STATES PATENT OFFICE.

JOHN RYAN, OF BALTIMORE, MARYLAND, ASSIGNOR TO ANTI-FRICTION BELT DRESSING COMPANY, OF BALTIMORE, MARYLAND.

DISPENSING-CAN.

1,311,013.

Specification of Letters Patent. Patented July 22, 1919.

Application filed March 21, 1917. Serial No. 156,347.

To all whom it may concern:

Be it known that I, JOHN RYAN, a citizen of the United States, residing at Baltimore, State of Maryland, have invented a new and 5 useful Dispensing-Can, of which the following is a specification.

This invention relates to dispensing cans particularly designed for use in pouring liquid dressing upon belts, one of the objects 10 of the invention being to provide the can with a nozzle of novel form whereby the size of the stream flowing from the nozzle can be controlled at will without requiring the use of moving parts.

15 Where thick liquid dressing is to be poured from a nozzle it is not possible to discharge the liquid from a small opening provided in the end of a gradually tapered nozzle because the liquid, by reason of its 20 thick viscous nature, clings to the walls of the nozzle and does not pour readily from a small opening. One of the objects of the present invention is to provide a nozzle having the discharge opening in its free end 25 reduced not by contracting the walls of the nozzle but, instead, by extending a barrier across said end thereby to produce a segmental opening which will allow streams of different sizes to flow from the nozzle, the 30 size of stream being dependent upon the position to which the nozzle is rotated before the can is tilted to pouring position.

With the foregoing and other objects in view which will appear as the description 35 proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown.

45 In said drawings:

Figure 1 is a side elevation of a dispensing can embodying the present improvements.

Fig. 2 is a central longitudinal section 50 through the nozzle of the can, said section being on an enlarged scale.

Fig. 3 is an enlarged section on line 3-3 Fig. 2.

Fig. 4 is an enlarged end elevation of the nozzle and showing the same turned to a position so as to permit the discharge of a small stream of liquid.

Fig. 5 is a view similar to Fig. 4 and showing the nozzle turned to another position to allow the escape of a larger stream.

Fig. 6 is a view similar to Figs. 4 and 5 and showing the nozzle turned to permit the escape of the largest possible stream.

Referring to the figures by characters of reference 1 designates the body of the can 65 which may be of any desired contour and which is provided preferably with a handle 2. Extending from the top of the can is a gradually tapered nozzle 3 and the free end portion of this nozzle is preferably screw 70 threaded as shown at 4 so as to be engaged by a cap 5 removably mounted on the nozzle. The free end of the nozzle has an inturned annular flange 6 and connecting this flange at diametrically opposed points is a bridging 75 strip 7 providing opposed segmental openings 8 between said strip and the flange 6.

When the can is to be used for dispensing liquid dressing, the cap 5 is removed and the can is then tilted so as to allow the liquid 80 contents thereof to pour through the lowermost segmental opening 8 in the nozzle. By turning the can so that one end portion of the lower opening 8 is lower than the other end portion, as shown in Fig. 4, the can can 85 be tilted so that the level of the liquid at the lower opening 8 will be on the line *a* in Fig. 4 or at a higher point. Thus streams of different sizes can be poured through the segmental opening 8. By turning the can 90 to the position shown in Fig. 5, a still broader stream can be discharged, the thickness of each stream being dependent upon the angle to which the can is tilted. By still further rotating the can the lower 95 opening 8 can be brought to the position shown in Fig. 6, whereupon a stream of the maximum width and depth can be discharged.

As has heretofore been stated, a construction such as described is particularly useful in dispensing thick viscous liquids or liquids which would not pour readily from a minute circular opening and the structure is particularly advantageous because of its simplicity 100 and the ease with which the size of the

stream can be controlled without the use of any valve mechanism or the like.

What is claimed is:—

- A dispensing can including a fixed nozzle
5 having a flat unobstructed free end and a diametrically disposed bridging element extending across said free end of the nozzle and forming opposed segmental outlet openings, the curved walls of the openings being

close to and concentric with the wall of the 10 nozzle.

In testimony that I claim the foregoing as my own, I have hereto affixed my signature in the presence of two witnesses.

JOHN RYAN.
